UNITED STATES PATENT OFFICE.

WILLIAM JAMES WRIGHT, OF FRANKLIN, PENNSYLVANIA, ASSIGNOR TO WRIGHT ENGINE COMPANY, OF PITTSBURGH, PENNSYLVANIA, A CORPORATION OF DELAWARE.

INTERNAL-COMBUSTION ENGINE.

1,073,652.

Specification of Letters Patent. Patented Sept. 23, 1913.

Application filed March 5, 1912. Serial No. 681,789.

To all whom it may concern:

Be it known that I, WILLIAM J. WRIGHT, residing at Franklin, in the county of Venango and State of Pennsylvania, have invented certain new and useful Improvements in Internal-Combustion Engines, of which the following is a specification.

My present invention is an improved compound internal combustion engine in which the parts are so arranged and designed that there will be no "dead center" to the engine as a whole and in which at the instant the ignition or explosion takes place after the high pressure pistons have compressed the working agent, one of such high pressure pistons will be moving on its working stroke to enable the full force and effect of the ignited charge at the instant of ignition to perform work in propelling the pistons along their working strokes, thus increasing the active power and efficiency of the engine.

The invention also embodies means whereby the high pressure section of the engine is in the nature of a duplex differential unit in which a plurality of cylinders and pistons are provided, the pistons being so arranged whereby the one passes its "dead center" in advance of the time when the other passes its "dead center" so that there will be no resultant "dead center" in the engine as a whole, and thus the objectionable features of this nature in the old types of engines are eliminated.

The invention further includes means for utilizing the heat energy which is usually wasted or dissipated through the cylinder walls of the engine and making such heat energy do work on the engine pistons.

My invention also includes means whereby the low pressure cylinder and its piston cooperate with the other parts in such a manner that during a part of the cycle of operation of the low pressure piston, it acts as a scavenging piston to draw off the burned mixture through the various ports of the high pressure cylinders and the intercommunicating ports between one of the high pressure cylinders and the low pressure cylinder, and simultaneously draw cold air in through the central air ports of one of the high pressure cylinders to draw the hot burned mixture into the low pressure cylinder against the head of the low pressure piston while it is traveling on a part of the downward stroke, thus leaving the cold air

in the high pressure cylinders and in the upper end of the low pressure cylinder.

The invention also includes a construction whereby when the exhaust ports are open they are opened next to the low pressure piston head so that on a succeeding part of its cycle of movement, the low pressure piston will force the old mixture through the exhaust ports without disturbing the cold air at the upper end of the low pressure cylinder.

Means are also provided for relieving any vacuum that may be formed in the cylinders during high speed running of the engine.

Again my invention provides a construction in which there are no intercommunicating valves between the several cylinders, and no exhaust valves to become overheated or worn, thus eliminating one of the chief objections to engines of the internal combustion type.

In addition to the foregoing, the invention also resides in those novel details of construction, combination and arrangement of parts, all of which will be first fully described, then specifically pointed out in the appended claims, reference being had to the accompanying drawings, in which:—

Figure 1 is a vertical longitudinal section on the line 1—1 of Fig. 2. Fig. 2 is a horizontal section on the line 2—2 of Fig. 1. Fig. 3 is a vertical longitudinal section on the line 3—3 of Fig. 2. Fig. 4 is a vertical cross section on the line 4—4 of Fig. 2. Fig. 5 is a detail horizontal section on the line 5—5 of Fig. 4. Fig. 6 is a detail vertical section on the line 6—6 of Fig. 3. Fig. 7 is a detail section on the line 7—7 of Fig. 1. Figs. 8 to 12 inclusive are diagrammatic views illustrating the operation of the invention.

In the drawings in which like numerals and letters of reference designate like parts in all the figures, 1 is the crank case, which is of the closed type, and which is provided with bearings 2 and 3, for the crank shaft 4.

5 and 6 designate the cranks of the crank shaft, there being two cranks employed for the three cylinders hereinafter referred to.

The crank case 1 is divided by a horizontal partition 7, into an upper chamber 55 and a lower chamber 8, which serves as an oil reservoir, the chambers 8 and 55 being in communication with one or more stand pipes 9 which project up from the bottom 110

of the partitions 7, a sufficient distance to always leave a layer of oil 10 in the crank chamber 55, whereby the overflow oil that passes through the pipes 9 will be sucked 5 into the chamber 55 in the form of a spray to lubricate the pistons and cranks and crank shaft bearings. On the down strokes of the several pistons, the air or vapor in the chambers 55 and 8 is compressed, while 10 on the up strokes the air or vapor in the chamber 55 is rarefied, thus causing a lesser pressure in chamber 55 than there is present in chamber 8. The air from chamber 8 then rushes through pipes 9 into chamber 15, 15 thereby atomizing the overflowing oil in the pipes 9 and forcing or drawing it as a spray into the chamber 55.

11 and 12 designate the high pressure cylinders, and 13 designates the low pressure cylinder. The cylinders 11, 12 and 13 together with their water jackets 16 are cast integrally and they have flanges 14 through which the bolts 15 pass to secure the cylinders to the crank case 1, with the interior of 25 which the cylinders communicate below their respective pistons. The high pressure cylinder 11 carries the high pressure piston 17 which is connected to the crank 6 through the principal connecting rod 19 and pin 18, 30 while the high pressure cylinder 12 has a piston 23 which is connected to the connecting rod 19 by an auxiliary rod 26 and pins 25 and 27, as best shown in Fig. 4 of the drawings. The cylinders 11 and 12 are 35 in communication through ports 20 with a common compression and ignition chamber 21 into which the spark plug 22 of the usual type projects. The pistons 17 and 23 are suitably packed in any desired manner and 40 the piston 23 has an annular groove or duct 24 between its ends, which will be herein-after again referred to. The high pressure cylinder 11 has a fuel intake port 28 with which the back check valve 29 communicates, the port 28 being controlled principally by the piston 17. The valve 29 communicates with the outlet valve mechanism 31, of the fuel charging pump 33, through the medium of a duct 30. The pump 33 is 45 mounted on the crank case 1 in the preferred construction, and the valve mechanism 31 includes a valve 32 that is operated by the pump piston 36 which operates in the pump cylinder. The piston 36 receives 50 its motion from a cam 39 that is secured at 40 to turn with the crank shaft 4, the cam 39 transmitting its motion through a connecting rod 38 and pin 37 to the piston 36. The working agent is admitted from the 55 fuel pipe through the back check valve 35 and port 34 into the pump casing 33 as required. The high pressure cylinder 11 is provided with one or more relief valves 41 which open when the engine is running rapidly under a light load to prevent formation

of a vacuum in the cylinders and thereby eliminate any drag on the pistons. The high pressure cylinder 12 is provided with a set of exhaust ports 42 which are controlled by the piston 23 and coöperate with 70 the annular groove 24 thereof. The cylinders 12 and 13 are also brought into communication at times by intercommunicating ports or ducts 43 and 44, the lower ones of the ducts 43, which align with the port 42, 75 serving as exhaust ports, while the upper ports 43 and port 44 serve purely as inter-communicating ports between the working chambers of the cylinders 12 and 13.

45 is the low pressure piston which is connected with the crank 5 by a connecting rod 47, pin 46, and crank connection 48.

49 is the oil pump which pumps the oil from the chamber 8 into the chamber 55, the pump 49 having its plunger 50 connected at 51 to the piston 36 to be operated thereby, and it also has its outlet or discharge port 52 arranged to deliver into the chamber 55, while the intake pipe 53 is provided with back check valves 54 and conveys the oil 90 from the chamber 8 to the pump 49 by which it is discharged into the chamber 55 through the outlet port 52, and back check valve 58.

The oiling system employed in my present 95 construction forms no part, *per se*, of the present invention as it forms the subject matter of my Patent #1,020,007 issued March 12, 1912.

56 is the fly wheel of the engine which 100 may be of the usual construction. The cylinder 11 is provided with a piston controlled air intake port 57 through which the scavenging agent is admitted into the cylinders at the proper time.

59 designates the intake and outlet pipes for the water jacket 16.

Operation: Referring now most particularly to the diagrammatic Figs. 8 to 12 inclusive, it will be perceived that when the 110 parts are positioned as indicated in Fig. 8, the cylinder 13 ahead of the piston 45 will be filled with fresh air undergoing compression. The working chambers of the cylinders 11 and 12 and the compression chamber 21 will contain a compressed new 115 charge which has just been ignited. It will be noticed that the piston 17 is just at its "dead center" while the piston 23 has passed its "dead center," therefore, at the 120 instant of the ignition of the charge the full force and effect of the initial pressure will be exerted on the piston 23 immediately, and as soon as the piston 17 starts on its working stroke, it also will be impelled 125 by the charge. When the parts are positioned as shown in Fig. 8, the piston 36 of the fuel pump will be drawing in a new supply of fuel through the valve 35 and at this time also the valve 32 and the back 130

check valve 29 will be closed. As the parts arrive at the position shown in Fig. 9, the pistons 17 and 23 are being impelled under the influence of the ignited working charge 5 in the cylinders 11 and 12. This charge is still at high pressure and at this time the piston 23 begins to uncover the auxiliary intercommunicating port 44 so that the high pressure working charge in the cylinders 11 and 12 may pass in part through 10 such port 44 into the cylinder 13 and unite with the compressed air in such cylinder to impel all three of the pistons under the influence of the working charge. While the 15 parts are moving from the position shown in Fig. 8 to the position shown in Fig. 9, the valves 29 and 31 will be closed and the valve 35 will remain open. It should also be understood that while the parts are moving 20 from the position shown in Fig. 8 to the position shown in Fig. 9 the ports 43 remain closed and the relief valves 41 together with the air port 57 are also closed. Now assume that the parts pass from the 25 position shown in Fig. 9 to the position shown in Fig. 10. In doing this, all three pistons 17, 23 and 45 are impelled under the influence of the expanding charge of working agent, the pressure of which is of course 30 rapidly falling. The pump piston 36 (Fig. 10) will also be moving on its upper stroke to compress the new charge of working agent in the pump cylinder 33. When the 35 parts have reached the position shown in Fig. 10, the piston 23 has reached the lowermost limit of its working stroke, and is about to begin its compression stroke, while the piston 17 still has a short distance of travel on its working stroke. The piston 17 40 in Fig. 10 is also uncovering the air inlet port 27 when the parts have arrived at the position shown in Fig. 10, whereby the piston 45 on its further movement from the position shown in Fig. 10 to the position 45 shown in Fig. 11 draws air in through the port 57 into the cylinders 11 and 12 and into the cylinder 13 to draw out the old charge from the cylinders 11 and 12 and replace them completely with air while sufficient air is admitted into the cylinder 13 50 so that after the cylinder 13 has been exhausted of the old charge, it will contain, theoretically, only fresh air. Now as the parts move from the position shown in Fig. 55 10 to the full line position shown in Fig. 11, the cylinders 11 and 12 will be scavenged and filled with air and fresh air will also be contained in the cylinder 13 above the dot and dash line which is the theoretical plane of demarcation between the fresh air and old or exhaust charge. Now as the parts move from the full line to the dotted line position shown in Fig. 11, and as soon as the piston 17 has closed the air port 57, the piston 36 of the charging pump will

open the valve 32 and the compressed charge of new working agent will pass into the cylinders 11 and 12 to displace some of the air therein through the auxiliary port 44, which being of small cross sectional area, 70 does not permit of a very rapid passage of the air between the cylinders 12 and 13. As the piston 23 moves on its compression stroke, from the full line to the dotted line position in Fig. 11, it will uncover the exhaust ports 42 bringing them in alinement with the groove 24 of the piston 23, so as to bring the lower ports or ducts 43 into communication with the exhaust ports or ducts 42, whereby the piston 45, will force the old charge beneath the dot and dash line in Fig. 13 through the lower ports 43 and grooves 24 and exhaust ports 42 to atmosphere. In moving from the dotted line position of Fig. 11 to the position shown in Fig. 12, the piston 36 begins its suction stroke, the valves 32 and 39 are closed, the pistons 17 and 23 will be compressing the new charge in the cylinders 11 and 12 and in the chamber 21, and the piston 45 will begin to compress air in the cylinder 13, while the exhaust port 42 will be nearly fully closed by the piston 23. Now when the parts move from the position shown in Fig. 12 to that shown in Fig. 8 the cycle 80 of operation of the engine as a whole, will 85 be completed.

From the foregoing it will be observed that I have provided a very efficient construction of engine in which the highest pressure of the working charge, which occurs at the instant of ignition, is brought to bear on a moving piston and not alone on a "dead" piston at the time it passes its "dead center," thus utilizing the entire expansive force of the ignited charge from the instant of ignition until the pressure of the charge has fallen to practically atmospheric pressure. Again my engine, it will be seen, provides an effective method of 100 utilizing the heat energy which usually is lost through radiation and conduction, to warm the incoming air which unites in the low pressure cylinder with the ignited new charge after the port 44, and subsequently 105 110 115 open up the ports 43, open up.

It will be noticed that by my construction and particularly by reference to Fig. 8, that the coöperation of the various pistons is such that the piston 23, operating in advance of the piston 17, delivers its power to the crank shaft under maximum pressure and as the pressure in the cylinders 11 and 12 is reduced, the second high pressure piston 17 will deliver its power to the crank shaft; as 120 125 the pressure of the working agent in the cylinders 11 and 12 is still further reduced the port 44 and subsequently the ports 43 open up whereby the compound piston or low pressure piston 45 which is several times 130

the area of the high pressure pistons, will deliver its power under working agent influence to the crank shaft in connection with the two high pressure pistons, 17 and 23, 5 thus making a very even delivery of the power to the crank shaft through the various distributions of the working agent pressures. In this manner I am able to dispense with heavy fly wheels, particularly by employing 10 two or more units on a single crank shaft in the well known manner.

I wish to mention that the construction herein shown and described is the preferred one, but I do not wish to be limited thereto 15 or to be understood as limiting myself thereto by the specific disclosure and description of the form of the engine herein referred to as many changes can be made in the construction and design of parts without departing from the invention as set forth in 20 the appended claims.

What I claim is:—

1. In a compound internal combustion engine, a high pressure section and a low pressure section, said low pressure section including a cylinder and a piston, said high pressure section including a plurality of cylinders and pistons, a crank shaft, a connecting rod between said crank shaft 25 and said low pressure piston, a differential connecting rod between said shaft and said high pressure pistons, piston controlled ducts between one of said high pressure cylinders and said low pressure cylinder, a common compression and ignition chamber for all of said high pressure cylinders, means for charging said high pressure cylinders with working agent, and means permitting the exhausting of said low pressure cylinder. 30

2. In a compound internal combustion engine, a high pressure section and a low pressure section, said low pressure section including a cylinder and a piston, said high pressure section including a plurality of cylinders and pistons, a crank shaft, a connecting rod between said crank shaft and said low pressure piston, a differential connecting rod between said shaft and said 45 high pressure pistons, piston controlled ducts between one of said high pressure cylinders and said low pressure cylinder, a common compression and ignition chamber for all of said high pressure cylinders, means for charging said high pressure cylinders with working agent, and means permitting the exhausting of said low pressure cylinder, and means for admitting a scavenging agent into said cylinders. 50

3. In an internal combustion engine, a low pressure cylinder and its piston, a high pressure cylinder and its piston, a crank shaft and connections between said crank shaft and said pistons, intercommunicating 60 ducts between said cylinders controlled by

both pistons, ducts in said high pressure cylinder controlled by said high pressure piston independent of the working chamber of said high pressure cylinder, certain of said intercommunicating ducts coöperating 70 with said high pressure cylinder ducts to form an exhaust passage from said low pressure cylinder to atmosphere, and means for supplying working agent to the working chamber of said high pressure cylinder. 75

4. In an internal combustion engine, a low pressure cylinder and its piston, a high pressure cylinder and its piston, a crank shaft and connections between said crank shaft and said pistons, intercommunicating ducts 80 between said cylinders controlled by both pistons, ducts in said high pressure cylinder controlled by said high pressure piston independent of the working chamber of said high pressure cylinder, certain of said intercommunicating ducts coöperating with said high pressure cylinder ducts to form an exhaust passage from said low pressure cylinder to atmosphere, means for admitting a scavenging agent into said high pressure cylinder, 85 and means for admitting working agent into said high pressure cylinder. 90

5. In an internal combustion engine, a pair of high pressure cylinders, a high pressure piston for each cylinder, a common compression and ignition chamber for said cylinders, a crank shaft, means causing one of said pistons to pass its "dead center" in advance of the passage of the other piston past its "dead center" when the new charge has 100 been compressed, a low pressure cylinder, and a low pressure piston operating in the same, a connection between the low pressure piston and the crank shaft, port connections between said low pressure cylinder and one 105 of said high pressure cylinders, an air inlet port for said high pressure cylinders controlled by the piston of that cylinder having the air inlet port, said air inlet port adapted to open while said low pressure cylinder is in 110 communication with the adjacent high pressure cylinder and said low pressure piston is still moving on its out stroke to cause air to be drawn into said high pressure cylinders and scavenge the same, and means for subsequently injecting a charge of gas into said high pressure cylinders to mix with the scavenging air and form the working charge. 115

6. In an internal combustion engine, a pair of high pressure cylinders, a high pressure piston for each cylinder, a common compression and ignition chamber for said cylinders, a crank shaft, means causing one of said pistons to pass its "dead center" in advance of the passage of the other piston past its "dead center" when the new charge has been compressed, a low pressure cylinder and piston, a connection between said crank shaft and said low pressure piston to cause said low pressure piston to pass through its cycle of 120 125 130

- operations at a later interval than that of the high pressure pistons, a controlled duct between said low pressure cylinder and the working chamber of one of said high pressure cylinders to admit the partly expanded charge from the high pressure cylinder into said low pressure cylinder to cause all of said pistons to simultaneously operate during a portion of their cycles under the influence of the ignited charge, means for charging said high pressure cylinders, and an exhaust duct for said low pressure cylinder.

7. In an internal combustion engine, a pair of high pressure cylinders, a high pressure piston for each cylinder, a common compression and ignition chamber for said cylinders, a crank shaft, means causing one of said pistons to pass its "dead center" in advance of the passage of the other piston past its "dead center" when the new charge has been compressed, a low pressure cylinder and piston, a connection between said crank shaft and said low pressure piston to cause said low pressure piston to pass through its cycle of operations at a later interval than that of the high pressure pistons, a controlled duct between said low pressure cylinder and the working chamber of one of said high pressure cylinders to admit the partly expanded charge from the high pressure cylinder into said low pressure cylinder to cause all of said pistons to simultaneously operate during a portion of their cycles under the influence of the ignited charge, means for charging said high pressure cylinders, and an exhaust duct for said low pressure cylinder, one of said high pressure cylinders having a controlled air intake port to coöperate with said low pressure piston to pass a scavenging agent into said cylinders when said intercommunicating port is open.

8. In an internal combustion engine, a pair of high pressure cylinders, a high pressure piston for each cylinder, a common compression and ignition chamber for said cylinders, a crank shaft, means causing one of said pistons to pass its "dead center" in advance of the passage of the other piston past its "dead center" when the new charge has been compressed, a low pressure cylinder and piston, a connection between said crank shaft and said low pressure piston to cause said low pressure piston to pass through its cycle of operations at a later interval than that of the high pressure pistons, a controlled duct between said low pressure cylinder and the working chamber of one of said high pressure cylinders to admit the partly expanded charge from the high pressure cylinder into said low pressure cylinder to cause all of said pistons to simultaneously operate during a portion of their cycles under the influence of the ignited charge, means for charging said high pressure cylinders, and an exhaust duct for said low pressure cylinder, controlled by said low pressure piston.

9. In an internal combustion engine, a pair of high pressure cylinders, a high pressure piston for each cylinder, a common compression and ignition chamber for said cylinders, a crank shaft, means causing one of said pistons to pass its "dead center" in advance of the passage of the other piston past its "dead center" when the new charge has been compressed, a low pressure cylinder and piston, a connection between said crank shaft and said low pressure piston to cause said low pressure piston to pass through its cycle of operations at a later interval than that of the high pressure pistons, a controlled duct between said low pressure cylinder and the working chamber of one of said high pressure cylinders to admit the partly expanded charge from the high pressure cylinder into said low pressure cylinder to cause all of said pistons to simultaneously operate during a portion of their cycles under the influence of the ignited charge, means for charging said high pressure cylinders, and an exhaust duct for said low pressure cylinder, one of said high pressure cylinders having a controlled air intake port to coöperate with said low pressure piston to pass a scavenging agent into said cylinders when said intercommunicating port is open, and means for relieving any vacuum that may be formed in said high pressure cylinders.

10. In an internal combustion engine of the character stated, a pair of high pressure cylinders and their pistons, a single

low pressure cylinder and its piston, a crank shaft, a connecting rod between said low pressure piston and said shaft, a differential connection between said shaft and said high pressure pistons to cause one of said high pressure pistons to pass its "dead center" in advance of the other at the commencement of their working strokes, a common compression and ignition chamber for both high pressure cylinders, intercommunicating ducts between said low pressure cylinder and the working chamber of one of said high pressure cylinders, said ducts being controlled by the said low pressure piston and the high pressure piston in the cylinder with which said ducts communicate, means for charging said high pressure cylinders with fresh working agent, said low pressure piston operating during a part of its cycle of movement to scavenge all of said cylinders.

12. In an internal combustion engine of the character stated, a pair of high pressure cylinders and their pistons, a single low pressure cylinder and its piston, a crank shaft, a connecting rod between said low pressure piston and said shaft, a differential connection between said shaft and said high pressure pistons to cause one of said high pressure pistons to pass its "dead center" in advance of the other at the commencement of their working strokes, a common compression and ignition chamber for both high pressure cylinders, intercommunicating ducts between said low pressure cylinder and the working chamber of one of said high pressure cylinders, said ducts being controlled by said low pressure piston and the high pressure piston in the cylinder with which said ducts communicate, means for charging said high pressure cylinders with fresh working agent, said low pressure piston operating during a part of its cycle of movement in coöperation with one of said high pressure pistons for drawing scavenging agent into all of said cylinders, said low pressure piston also operating under another part of its cycle of movement in coöperation with the same high pressure piston for exhausting the low pressure cylinder contents to atmosphere.

13. In an internal combustion engine, a pair of high pressure cylinders and their pistons, a single low pressure cylinder and its piston, the first of said high pressure cylinders having a piston controlled air inlet port, a fuel charging pump for injecting fuel into said first high pressure cylinder at intervals, a compression and ignition chamber for said high pressure cylinders, intercommunicating ducts between the second of said high pressure cylinders and said low pressure cylinder, said last named ducts being controlled by both the second high pressure piston and the low pressure piston, said

second high pressure cylinder having exhaust ports independent and out of communication with the working chamber of the same, said exhaust ports being controlled by said high pressure piston, intercommunicating exhaust ducts between said second high pressure cylinder and said low pressure cylinder, and controlled by said low pressure piston and said second high pressure piston, a single crank shaft, means connecting the pistons with said crank shaft to impart motion thereto, substantially as shown and described.

14. In an internal combustion engine, a pair of high pressure cylinders and their pistons, a single low pressure cylinder and its piston, the first of said high pressure cylinders having a piston controlled air inlet port, a fuel charging pump for injecting fuel into said first high pressure cylinder at intervals, a compression and ignition chamber for said high pressure cylinders, intercommunicating ducts between the second of said high pressure cylinders and said low pressure cylinder, said last named ducts being controlled by both the second high pressure piston and the low pressure piston, said second high pressure cylinder having exhaust ports independent and out of communication with the working chamber of the same, said exhaust ports being controlled by said high pressure piston, intercommunicating exhaust ducts between said second high pressure cylinder and said low pressure cylinder, and controlled by said low pressure piston and said second high pressure piston, a single crank shaft, means connecting the pistons with said crank shaft to impart motion thereto, the connection between said high pressure pistons and the crank shaft including a differential connection whereby one of said high pressure pistons will pass its "dead center" in advance of the other high pressure piston, substantially as shown and described.

15. In an internal combustion engine, a pair of high pressure cylinders and their pistons, a single low pressure cylinder and its piston, the first of said high pressure cylinders having a piston controlled air inlet port, a fuel charging pump for injecting fuel into said first high pressure cylinder at intervals, a compression and ignition chamber for said high pressure cylinders, intercommunicating ducts between the second of said high pressure cylinders and said low pressure cylinder, said last named ducts being controlled by both the second high pressure piston and the low pressure piston, said second high pressure cylinder having exhaust ports independent and out of communication with the working chamber of the same, said exhaust ports being controlled by said high pressure piston, intercommunicating exhaust ducts between said

second high pressure cylinder and said low pressure cylinder, and controlled by said low pressure piston and said second high pressure piston, a single crank shaft, means connecting the pistons with said crank shaft to impart motion thereto, the connection between said high pressure pistons and the crank shaft including a differential connection whereby one of said high pressure pistons 5 will pass its "dead center" in advance of the other high pressure piston, said intercommunicating ducts between said low pressure cylinder and the working chamber of the first of said high pressure cylinders 10 including a main set of ducts and an auxiliary duct, the auxiliary ducts being arranged to be open in advance of the main ducts.

16. In an internal combustion engine, a high pressure cylinder, a high pressure piston operating in said cylinder, a low pressure cylinder and a low pressure piston operating in said low pressure cylinder, valveless intercommunicating ducts effecting 15 communication between said two cylinders and controlled by the respective pistons, means for charging the high pressure cylinder with a new charge while said intercommunicating ducts are closed, connections between said pistons causing one of 20 said pistons to travel in advance of the other, exhaust ports for said high pressure cylinder, said high pressure piston having a passage effecting communication between 25 said exhaust ports and certain of said intercommunicating ports at times to permit the spent charge from said low pressure cylinder to pass into said high pressure cylinder, around said high pressure piston, 30 and through said exhaust ports of said high pressure cylinder to atmosphere.

17. In an internal combustion engine, a pair of high pressure cylinders, a high pressure piston for each cylinder, a common compression and ignition chamber for said cylinders in constant communication with the same, a crank shaft, means causing one of said high pressure pistons to pass its "dead center" in advance of the passage of 45 the other piston past its "dead center" when the new charge has been compressed, a low pressure cylinder, a low pressure piston intercommunicating ducts between one of said high pressure cylinders and said low pressure cylinder controlled by the respective high and low pressure pistons, and means for discharging the spent charge 50

from the low pressure cylinder to atmosphere, together with means for charging said high pressure cylinders with new working agent. 60

18. In an internal combustion engine, a pair of high pressure cylinders, a high pressure piston for each cylinder, a common compression and ignition chamber for said cylinders in constant communication with the same, a crank shaft, means causing one of said high pressure pistons to pass its "dead center" in advance of the passage of the other piston past its "dead center" 70 when the new charge has been compressed, a low pressure cylinder, a low pressure piston intercommunicating ducts between one of said high pressure cylinders and said low pressure cylinder controlled by the respective high and low pressure pistons, and means for discharging the spent charge from the low pressure cylinder to atmosphere, together with means for charging said high pressure cylinders with new working agent, and means for admitting scavenging air into said high pressure cylinders at other times. 75

19. In an internal combustion engine, a pair of high pressure cylinders, a high pressure piston for each cylinder, a common compression and ignition chamber for said cylinders, a crank shaft, a differential connection between said high pressure pistons with said crank shaft, said differential connection causing one of said high pressure pistons to pass its "dead center" in advance of the passage of the other high pressure piston past its "dead center," a low pressure cylinder and its piston, a connection 90 between said low pressure piston and said crank shaft, intercommunicating ducts between one of said high pressure cylinders and said low pressure cylinder, controlled by the respective high and low pressure pistons, and means controlled by one of said high pressure pistons for passing the spent mixture to atmosphere under the influence of said low pressure piston when working on its exhausting stroke, together with 95 means for admitting new charges of working agent to said high pressure cylinders and for withdrawing the old charges from said high pressure cylinders into said low pressure cylinder. 100
